UNITED STATES PATENT OFFICE.

KURT ROEBER, OF HALLE-ON-THE-SAALE, GERMANY.

TRANSFORMER.

1,315,419.

Specification of Letters Patent. Patented Sept. 9, 1919.

Application filed November 3, 1914, Serial No. 870,044. Renewed January 21, 1919. Serial No. 272,341.

To all whom it may concern:

Be it known that I, KURT ROEBER, a German citizen, and resident of Halle-on-the-Saale, Germany, have invented certain new 5 and useful Improvements in Transformers, of which the following is a specification.

My invention relates to so-called "measuring instrument transformers", which are used for instance in alternating current central stations for the purpose of avoiding the use of high tensions or large currents directly in measuring instruments; my invention refers in particular to so-called "current transformers" which are used for the 10 above named purpose in connection with ammeters or with the current coils of watt meters or the like.

In order to be theoretically perfect, such instrument transformers must fulfil two conditions which do not exist in case of power 20 transformers;

1. The phase displacement between the primary and the secondary terminal potential in case of voltage transformers, and the 25 phase displacement between the primary and the secondary current in case of current transformers, should be exactly 180° at all practically possible load values of the transformer.

30 2. The relation of the primary and secondary potential or current should remain the same for all practical load values of the transformer.

In the light of these conditions the instrument transformers constructed heretofore are rather imperfect. As may be known to those skilled in the art, they can be improved already to a considerable extent 35 when they are connected with a condenser for compensating the no-load current.

In the present invention a general improvement of these transformers is obtained principally by making the phase displacement between the primary and the secondary 45 potential or current independent to a larger degree from the load of the transformer than was the case up to the present. And in case of instrument transformers having condensers, I make an improvement by keeping the value of this phase displacement at varying transformer loads closer to 180° than is the case in the known instrument transformers which have condensers.

Aside from these improvements, another 50 improvement results as a consequence ac-

cording to which the ratio of the transformers becomes independent from the load to a larger degree than in case of ordinary transformers. However this fact may be mentioned here only incidentally.

60

I shall explain the character of my invention taking a current transformer as an example and it may be presumed that the secondary terminals of the transformer are permanently connected with the same non-inductive or inductive load resistance.

65

My invention is illustrated in the accompanying drawings in which:

Figure 1 is a diagram used for explaining the problem to be solved by my invention.

70

Figure 2 is a diagram for explaining the fundamental theoretical idea underlying my invention;

Fig. 3 is a wiring diagram of a preferred 75 practical form, and

Fig. 4 is a detail of a particular mechanical feature of the apparatus constructed according to my invention.

It is well known that in transformers of 80 the character referred to, the relation and the phase displacement between the primary and secondary current is influenced by the no-load current, that is to say, influenced by the component of the primary current which 85 is necessary for producing the magnetic field in the iron core of the transformer. This no-load current is again usually considered as a resultant of two components, i.e., the "watt-less component" or "magnetizing component", which represents the pure magnetizing current of the iron, and the "watt component" which represents the current used for covering the iron losses through hysteresis and eddy currents. If the well 90

known vector-diagram is plotted indicating for the several load values that is to say, for the several values of the current, in the secondary transformer circuit closed as presumed above, the corresponding values of the 100 "watt-less component" and of the "watt component" of the no-load current together with their relative phase displacement and the displacement over the secondary current, and if from the components of the no-load current 105 and of a current equal to the secondary current but displaced 180° , the primary current is defined as a resultant in the usual manner, it is found that the phase displacement between the primary current and the secondary 110

current of the transformer varies with the varying secondary current because the magnetizing component of the no-load current does not vary proportionately to the secondary current of the transformer. The reason for this is found in the varying permeability of the iron, because on account of this variation the magnetizing component of the no-load current is not proportional to the generated magnetic field and consequently also not proportional to the electro-motive force induced by the field and lastly, for the same reason, it is not proportional to the secondary current which is generated in the secondary circuit by the induced electro-motive force. The differences in the proportion between the magnetizing component and the electro-motive force which alone I shall hereinafter use as comparative values, compared with the exact proportionality, are according to experiments with current transformers of such character that when the electro-motive force rises from zero to a value corresponding with maximum load, the magnetizing component increases slower than the electro-motive force, because the magnetic conditions of the transformer iron which exist in this case are represented by points in the magnetizing curve which are located below the point of maximum permeability.

Through my invention I obtain a better ratio between the magnetizing component of the no-load current on one hand and the induced electro-motive force and thus the secondary current on the other hand. I gain this advantage by adding to the actual no-load current of the transformer to which reference was made heretofore, a current which I shall call hereinafter "additional no-load current", so that from the actual no-load current and the additional no-load current, a new no-load current results which I shall call "total no-load current". The additional current is proportioned so that its magnetizing component grows faster than the induced electro-motive force. Thus the magnetizing component of the total no-load current will then become more proportionate to the induced electro-motive force, because the faster increase of the new component compensates the too slow increase of the actual magnetizing component.

It can be easily seen that a transformer having a total no-load current as described above, can be corrected quite perfectly through the connection with a condenser to compensate the total no-load current, whereby this condenser may be for instance in parallel to the load resistance and be connected at the terminals of the secondary winding or it may be connected to a separate secondary winding. The reason for this good compensation is that the current which occurs in the primary winding of the

transformer, owing to the connection with the condenser, is proportionate to the induced electro-motive force and, as is known, has a phase displacement of 180° against the magnetizing component of the no-load current, and its compensating effect on the no-load current, strictly speaking, consists in compensating the magnetizing component of the no-load current. Thus in case of a transformer whose total no-load current has a magnetizing component proportionate to the induced electro-motive force, this compensation is substantially perfect, whereas in an ordinary transformer it can only be imperfect.

In order to illustrate these fundamental theoretical principles of my invention, I have plotted in the coördinate system in Fig. 1 of the drawings, the curve C_1 which represents the relation between the magnetizing component of the actual no-load current and the induced E. M. F. of a current transformer wherein the several values of the induced E. M. F. (E) are taken as ordinates and the corresponding values of the magnetizing component (I_m) of the actual no-load current are taken as abscissæ from O to the right side of the abscissæ axis. The curve C_1 , in its character is the lower portion of the magnetizing curve of the iron, of which the transformer core is made. The point C_1^o of the curve having the abscissa I_m^o and the ordinate E^o may correspond with the full load of the transformer. In the same coördinate system I have represented the relation between the induced E. M. F. and the capacity current (I_c) by the straight line C_2 which current occurs in the primary winding of the transformer owing to the connection of the condenser to the secondary terminals. The point C_2^o of the straight line whose ordinate is E^o and whose abscissa is I_c^o again corresponds with the full load. Since I_c is plotted from O toward the left side of the abscissæ axis, the abscissæ I_m , I_c and the corresponding common ordinate E have the same corresponding positions which the vectors of these electric values have in a vector diagram having vectors rotating in the sense of the arrow. Thus the lines $O I_m$, $O E$, $O I_c$, $O I_m^o$, $O E^o$, $O I_c^o$ may also be considered as vectors. Now I have chosen the current intensity I_c^o equal to the current intensity I_m^o . Owing to this selection the compensation of the magnetizing component of the actual no-load current in case of full load, is in the transformer in question perfect at the value E^o of the induced E. M. F., in all other cases imperfect, because the portion i_m of the magnetizing component I_m between the curve C_1 and the straight line $O C_2^o$, represented especially by the curve C_3 , remains uncompensated. In Fig. 2, I have illustrated the underlying theoretical idea of my

invention. Aside from the curve C_1 , I have plotted the curve C_4 having the abscissa j_m and the ordinate E , which represents the relation between the magnetizing component of the additional no-load current and the induced E. M. F. which is necessary for the complete compensation of the magnetizing component of the total no-load current by means of a condenser. The abscissa j_m of curve C_4 when added to the abscissa 1_m of curve C_1 , results in the abscissa J_m of a straight line C_5 , which thus represents a linear relation between the magnetizing component of the total no-load current and the induced E. M. F. Now for the perfect compensation of this magnetizing component, a condenser is necessary and sufficient which at full load of the transformer, i.e., at the value E^o of the induced E. M. F., produces in the primary winding of the transformer a capacity current whose value is $J^o = J_m^o$. This capacity current is represented in its dependency from the induced E. M. F. by the straight line C_6 in Fig. 2.

An additional no-load current having a magnetizing component whose relation to the induced E. M. F. has the character indicated by the curve C_4 in Fig. 2, is produced in the following manner: I arrange the iron core so that it is magnetized by the current in a secondary winding of the current transformer and I make this iron core of such dimensions and of such material that when the load of the current transformer is increased, the state of highest permeability has passed already at small values of this load, at any rate before the maximum load is reached and so that at the higher load values of the transformer the condition of saturation is approached. In order to magnetize the core with the aid of a secondary current of the current transformer, I place it within a coil or winding d , Fig. 3, having its ends connected with the ends of a secondary coil or winding of the current transformer. I may use for this purpose either the same secondary coil or winding of the transformer, to which the load resistance is connected as, for instance, coil S , Fig. 3, and I then connect coil d containing the auxiliary core to the terminals of said secondary coil or winding S of the transformer. This modification is so obvious that I have omitted the illustration thereof. I may, however, also use a special secondary winding on the current transformer for this purpose. This modification is shown in Fig. 3 at c . Therefore when using in the claims the plural "secondary windings" with reference to the current or instrument transformer I mean to imply any suitable number of secondary windings, whether they be connected with the load resistance or whether they be separate windings arranged solely for the purpose of feeding coil d , and

by this plural I mean to cover both forms of connection, referred to above, as equivalents. If a condenser is used at the same time in order to compensate the total no-load current, I prefer for reasons to be explained hereinafter, to connect the condenser to a secondary winding on the iron core so that the condenser is supplied from the current transformer, or as it will be termed hereinafter the "main transformer" by way of an additional or auxiliary transformer.

This modification of my invention is illustrated diagrammatically in Fig. 3. In this figure a represents the iron core of the main transformer, p its primary, s its secondary winding, the latter being connected in circuit with a measuring instrument m as a load resistance. c is another secondary winding of the main transformer. It is connected with the primary winding d of the auxiliary transformer whose iron core and secondary winding is represented at b and e respectively. In circuit with secondary winding e is the condenser k . In order to understand that coil d with its iron core b has the effect upon the main transformer described above, it is first presumed that the condenser k is removed. In this case coil c of the main transformer is then merely loaded with a very large inductance; thus it carries the current which lags in phase over the secondary E. M. F. of the main transformer at an angle approaching closely 90° and thus a current is produced in the primary winding p of the main transformer whose phase is approximately the same as the phase of the actual no-load current of the main transformer. This current is called "additional no-load current" because it also occurs in the primary coil of the main transformer when the circuit of the secondary coil c of the main transformer is open.

If now the condenser k is connected to the secondary coil e of the auxiliary transformer, coil c of the main transformer is loaded with a resistance of particular character. In this case in the coil c aside from the current for producing the field in the iron core b of the auxiliary transformer, also the capacity current flows which occurs in the primary coil d of the auxiliary transformer owing to this condenser connection. Curve C_7 in the case assumed in Fig. 2 gives an idea of the relation between the value of this mixed load current of coil c and the E. M. F. induced in this coil. The abscissa i of this curve is equal to the algebraic sum of the abscissæ J_e and j_m . However curve C_7 does not exactly represent the above mentioned relation because in this curve the watt component of the current flowing in coil c is not considered.

Curves C_1 and C_7 are located symmetrically to the ordinate axis. From this it may be seen that it is permissible to consider the

current i_c , whose dependency from E is represented by the curve C_7 , as compensating current for the magnetizing components of the actual no-load current of the main transformer. This view is based upon the following deductions. When explaining the character of the curve C_7 hereinbefore, not only the watt component of the current in the coil c of the main transformer was disregarded, but also the ohmic and inductive drop in potential in the coils c , d and e . Now I have found that these drops in potential influenced the character of curve C_7 and that it is possible by affecting these potential drops, especially the inductive one, to conform curve C_7 closely to C_1 . For this purpose I propose for instance to produce an artificial stray flux for the primary coil d of the auxiliary transformer by placing the secondary coil e only on one of the two parallel portions of the iron core b or by providing a special iron core excited by coil d alone. By suitably dimensioning the stray path it may be brought about that the iron in the stray path is not yet saturated at the maximum values of the E. M. F. affecting coil d ; or it may be also brought about that it is already saturated at the smallest values of this E. M. F.; it may also be brought about that it commences to be saturated at a medium value of the E. M. F. According to which of the three conditions exists the curvature of curve C_7 in Fig. 2 is greater or smaller, or the curvature may be smaller in its lower portion and greater in its upper portion.

I have now explained the general points on which my invention is based and according to which it may be reduced to practice. 40 In detail the dimensions of the coils and iron cores which are necessary for the construction according to my invention, must be ascertained by calculation or experiment according to the particular type of instrument transformer to be used.

The possibility already mentioned of utilizing the potential drops in the coils d , e , of the auxiliary transformer according to Fig. 3 for affecting the form of curve C_7 in Fig. 2, and to thus obtain as perfect an effect as possible, is one of the reasons which has prompted me to prefer the modification shown in Fig. 3 of the drawings. A second and very important reason for using this form is that in this case, the condenser k is protected from too high a potential and it may therefore be made quite small and be cheap to build. This has the following reasons: If, through some cause the circuit of the load resistance is interrupted, the field in the iron core of the main transformer assumes very high values whereas the demagnetizing effect of the secondary winding is not present in that case. Consequently, the 65 E. M. F. effective in the circuit of the pri-

mary coil d of the auxiliary transformer increases far beyond the values which it can assume in case of normal operation and it is immaterial in this case whether the coil d is connected to a special secondary coil e 70 or connected to the secondary coil d of the main transformer in parallel to the load resistance. Now the field in the iron core of the auxiliary transformer cannot increase in the same measure because this iron core is 75 already saturated at small values of the E. M. F. of the main transformer which occur under normal conditions. Consequently, the condenser k , even if the load resistance should be cut off at the full primary current of the main transformer, would not be 80 subject to an appreciably higher potential than exists under normal conditions at full load of the main transformer with the load resistance connected.

The iron cores necessary for the construction according to my invention have very small cross sections. I therefore prefer to form these cores by bending sheet iron strips into circular or rectangular shape and by 90 joining their ends. In order to get as good magnetic connection of the ends as possible, they may be electrically welded together. This form is shown in Fig. 4 of the drawings. In this modification d represents the 95 primary coil, e the secondary coil of the auxiliary transformer whose iron core is b which is common to the primary and secondary coil; f is an iron core which is energized by the primary coil alone, in order to increase the stray flux of this coil. The iron cores b and f are bent together from sheet iron strips with their ends welded together as shown at B and F. I should mention that the underlying principles of my invention described with respect to a current transformer as an example, may also be applied in case of a voltage transformer. However, the importance of my invention is not as great for voltage transformers as for 100 current transformers, because the range within which the potential varies from its normal value, is small compared with this normal value, so that also the magnetic flux density in the iron core of the transformer 115 and with it the permeability of the iron is changed only little, and further because the influence of the magnetizing component of the no-load current becomes effective only at the primary potential drops which themselves constitute only a small fraction of the primary potential.

I have at the beginning stated the decrease of the effect of the transformer load on the phase displacement between the primary and the secondary current or voltage as one of the chief features and advantages of my invention. However, great benefit may be derived from my invention also by permitting the usual variation in phase displace- 130

ment, common to the ordinary instrument transformers, also to exist in my case, but by making the instrument transformer itself on the other hand, smaller and thus cheaper.

- 5 This is permissible because when employing the features according to my invention higher values of the magnetic flux density in the iron core of the transformer are permissible, which values are located in the 10 range of the magnetizing curve in which the permeability strongly increases with the field intensity. Lastly through my invention the instrument transformer is improved as well as its manufacture cheapened.

15 I claim:-

1. The combination with an instrument transformer having an iron core, a primary winding and secondary windings thereon, of an auxiliary iron core carrying suitable 20 windings connected to some of the secondary windings of the instrument transformer to magnetize said auxiliary core and having such dimensions and being constructed of such material that the iron transgresses 25 the state of maximum permeability before the maximum load of the instrument transformer is reached when its load is increased.
2. The combination with a current transformer having an iron core, a primary winding and secondary windings thereon, of an auxiliary transformer having a primary winding connected to one of the secondary windings of the current transformer and also having itself a secondary winding and 30 a condenser in circuit therewith and having an iron core of such dimensions and material, that its iron transgresses the state of maximum permeability before the maximum load of the current transformer is reached 35 when its load is increased.
3. The combination with a current transformer having an iron core and a primary 40

winding and secondary windings thereon, of an auxiliary transformer having a primary winding connected to one of the secondary 45 windings of the current transformer, and having itself a secondary winding having itself a condenser in circuit with it, said auxiliary transformer having an iron core of such dimensions and such material that the 50 iron transgresses the state of maximum permeability before the maximum load of the current transformer is reached when the load is increased and magnetic means operatively connected with the primary coil 55 of the auxiliary transformer for increasing the stray flux of said coil.

4. The combination with a current transformer having an iron core and thereon a primary and one secondary winding connected to a load resistance and having a second separate secondary winding, of an auxiliary transformer having a primary winding connected to said separate secondary winding of the current transformer, a secondary winding on the auxiliary transformer having a condenser in circuit with it, said auxiliary transformer having an iron core of such dimensions and of such material that the iron transgresses the state of maximum 60 permeability before the maximum load of the current transformer is reached when the load is increased, and an iron core operatively connected with the primary winding 65 of the auxiliary transformer for increasing 70 the stray flux of this winding.

In witness whereof I have hereunto set my signature in the presence of two subscribing witnesses.
